DRAIN VALVE APPARATUS

John Canetta, Wilkinsburg, Pa., assignor to The Westinghouse Air Brake Company, Wilmerding, Pa., a corporation of Pennsylvania

Application May 31, 1943, Serial No. 489,181

7 Claims. (Cl. 303—88)

This invention relates to drain valve apparatus for receptacles containing fluid under pressure, and more particularly to a drain valve equipment embodying means for effecting periodic operation thereof at predetermined intervals.

The receiving reservoirs of a compressed air system, such as the main reservoirs or after-coolers associated with an air brake system on a locomotive, are customarily equipped with drain valve devices which are designed for operation from time to time to eject condensate accumulating within the receptacle. It has been found desirable to provide such drain valve devices with means automatically operative to cause periodic operation at predetermined intervals.

The principal object of my invention is to provide an improved automatic drain valve apparatus embodying a fluid pressure actuated timing mechanism, which may be employed on a locomotive throughout a long service period without requiring expensive repairs or adjustments.

Another object of the invention is to provide an apparatus of the above description including a timing valve mechanism operative at predetermined intervals to effect quick, positive movement of the discharging valve portion of the drain valve device associated with the pressure reservoir.

Other objects and advantages of the invention will appear in the following more detailed description thereof, taken in connection with the accompanying drawing, in which

Fig. 1 is a diagrammatic view, mainly in section, of a drain valve apparatus constructed in accordance with one form of the invention; and

Fig. 2 is a diagrammatic elevational view, also in section, of a timing valve device embodying a different form of the invention and adapted to be substituted for the corresponding device shown in Fig. 1.

Embodiment in Fig. 1

The equipment illustrated in schematic form in Fig. 1 of the drawing comprises a main reservoir 1, which is adapted to be charged with compressed air by means of a suitable compressor, not shown, and which has associated therewith a fluid pressure actuated drain valve device 2, and a timing valve device 4. It will be understood that in actual practice the drain valve device and timing valve device may be associated with more than one main reservoir, or with an aftercooler or the like, depending upon the equipment carried by the locomotive.

The drain valve device 2 comprises a casing section 5 suitably secured to the bottom of the

main reservoir 1, a casing section 6 bolted to the casing section 5, and a flexible diaphragm 7 which is clamped between the two casing sections in a canted position, forming on one side thereof a pressure chamber 8 and on the opposite side a chamber 9 communicating with a drainage tube 10. Formed in the casing section 5 is a condensate collecting chamber 12 which communicates by way of a passage 13 with the interior of the main reservoir 1. A bore 14 connects the chamber 12 with a valve chamber 15, also formed in the casing section and communicating by way of a bore 16 with the chamber 9. A double valve element 18 disposed within the valve chamber 15 is engageable with a seat 19 for controlling communication between the chambers 12 and 15, or alternatively with a valve seat 20 for controlling communication between chambers 15 and 9. The double valve element 18 is supported through the medium of a fluted stem 23 slidably fitting the bore 14, and a similar stem 24 slidably mounted in the other bore 16, it being noted that the valve element and stems are inclined in alignment with the axis of the canted diaphragm 7. The fluted stem 24 operatively engages a follower member 25 which is attached to the diaphragm 7, and which is subject to the force exerted by a coil spring 26 interposed between the follower element and the upper wall of the chamber 9. The spring 26 normally urges diaphragm 7 downwardly and into engagement with a stop portion 27 of the casing. A coil spring 28 is interposed between the fluted stem 23 and an upper wall of the chamber 12 for urging the double valve element 18 downwardly into engagement with the seat 20, as shown in the drawing, in which position of the valve element communication is maintained between the chambers 15 and 12.

40 The timing valve device 4 has a casing structure comprising a main section 30 having an end wall 31 and a central wall 32, and carrying at the open end a cover section 33, and supporting a casing section 34 adjacent the wall 31. Formed in the casing section 34 is a valve chamber 37 which communicates by way of a passage forming a valve seat 38 with a timing chamber 39 within the casing section 30, and also by way of a choke or restricted passage 40 and pipe 41 with the main reservoir 1. A suitable air straining assembly 42 is preferably interposed in the communication between the restricted passage 40 and pipe 41.

45 In the casing section 30 between the central wall 32 and the cover section 33 is formed a bore

55 in the casing section 30 between the central wall 32 and the cover section 33 is formed a bore

45, in which is slidably mounted a valve piston 46 that is normally urged into seating engagement with a seat rib 47 carried by the wall 32, under the force exerted by a coil spring 49 interposed between the valve piston and cover section 33. A rod 57 is secured to the valve piston 46 and extends axially thereof through the opening within the seat rib 47 and into the timing chamber 39, where the end of the rod is secured to a cage structure 53 having an interior chamber containing a spring 54. The spring 54 is adapted to bear against a collar formed on the end of a valve stem 55 which is operatively mounted in the cage structure 53 and terminates in a valve 56, which is disposed in the valve chamber 37 and is adapted for engagement with the seat 38. It will be noted that with the relatively large valve piston 46 held against the seat rib 47 by the spring 49, the valve 56 is maintained in an unseated position.

Referring again to the valve piston 46, it will be observed that this element is cylindrical in shape, and that the open end thereof opposite the portion engageable with the seat rib 47 carries an annular rib 60, which is adapted to be moved into engagement with an annular gasket 61 carried by the cover section 33 for controlling communication between a port 62 in the casing and the bore 45, which is at all times open to the atmosphere by way of a restricted exhaust passage 63. The port 62 communicates by way of a pipe 65 with the pressure chamber 8 of the drain valve device 2, and is also open to the atmosphere through a choke 66 connected to the pipe. One end of the port 62 is adapted to be uncovered, upon movement of the valve piston 46 to the right, to establish communication between the pipe 65 and a chamber 48 formed between the end face of the valve piston and the wall 32.

In operation, fluid supplied under pressure to the main reservoir 1 flows therefrom by way of pipe 41, strainer 42 and choke 48, and past the normally unseated valve 56 to the timing chamber 39, at a rate determined by the size of the restricted passage. The gradually increasing pressure of fluid in the timing chamber 39 acts against the portion of the valve piston 46 exposed within the seat rib 47 until, after a predetermined interval, this fluid pressure becomes high enough to overcome the opposing force exerted by the spring 49, whereupon the valve piston is moved away from the seat rib. Fluid under pressure is thus admitted to the chamber 48 and acts over the entire pressure area of the valve piston, which is thereby quickly forced to its right-hand position, with the rib 60 held in engagement with the gasket 61. In so moving, the valve piston 46 uncovers the port 62, through which fluid under pressure flows from the chamber 48 to the pipe 65 and thence to the chamber 8 of the drain valve device 2, the elements of which will be understood to have been initially positioned as shown in Fig. 1. It will be apparent that although fluid under pressure is meanwhile gradually vented from the pipe 65 through the restricted branch communication 66, the rate of such venting is so limited as to permit the initial increase in fluid pressure in the chamber 8 necessary to effect immediate operation of the drain valve device.

At the same time, as the valve piston 46 moves to the right, as viewed in Fig. 1, the valve 56 operatively connected thereto is brought into seating engagement with the seat 38 for cutting off further supply of fluid under pressure from the main reservoir 1 to the timing chamber 39. The

spring 54 is adapted to yield upon movement of the valve 56 to seated position in order to compensate for the somewhat greater traverse of the valve piston 46.

The pressure of fluid supplied to the pressure chamber 8 of the drain valve device 2 meanwhile operates the diaphragm 7, follower member 25, and stem 24 to shift the double valve element 18 away from the lower seat 20 and into engagement with the upper seat 19, in opposition to the combined forces of the springs 26 and 28. As the double valve element 18 traverses the distance between the two seats, the pressure of fluid contained in the main reservoir 1 acts against the water which has accumulated in the chambers 12 and 15 to effect quick discharge thereof, the water being driven out past the valve seat 20 and through the chamber 9 and drainage tube 10. It will be understood that this movement of the double valve element 18 into engagement with the upper seat 19 is accomplished quickly, so that the amount of compressed fluid required for the operation to expel the condensate is limited.

Since the valve 56 has been operated to cut off the supply of compressed fluid from the main reservoir, as just explained, the quantity of compressed fluid bottled up in the timing chamber 39 and in the communications therewith leading to the pressure chamber 8 of the drain valve device 2 is gradually reduced by flow from the pipe 65 through the restricted atmospheric communication 66. When the escape of fluid to the atmosphere has effected a predetermined reduction in the fluid pressure in the chamber 48 acting on the valve piston 46, the spring 49 is rendered effective to move the valve piston into engagement with the seat rib 47, thus reestablishing communication between the port 62 and the atmospheric exhaust passage 63. The pressure of fluid in the diaphragm chamber 8 of the drain valve device 2 is then reduced to that of the atmosphere, and the springs 28 and 26 again become effective to move the double valve element 18 and the associated elements downwardly into the position in which they are shown in Fig. 1. While the double valve element 18 is thus moved from the seat 19 to the seat 20, it effects another discharge of accumulated condensate from the chamber 12, as hereinbefore explained.

The various elements of the drain valve apparatus are thus returned to their initial positions, ready for the next cycle of operation.

Embodiment in Figure 2

In Fig. 2 of the drawing there is illustrated a different form of timing valve device 70, which, like the timing valve device 4 of Fig. 1, is adapted to be associated with a main reservoir and drain valve device, the latter elements of the complete apparatus having been omitted in this view. It will be understood that the 4'a shown in Fig. 2 is adapted to be connected to the main reservoir, and that the pipe 65'a is arranged to be connected to the pressure chamber of the drain valve device, which is adapted to function in cooperation with the timing valve device 70 in the same manner as has been described in connection with the similar equipment shown in Fig. 1. The timing valve device 70 comprises a pipe bracket 72 to which the pipes 65'a and 41'a may be attached and a casing section 73 mounted on the pipe bracket and having formed therein a spring chamber 74, a valve chamber 75, and a piston valve bore 76 that is arranged substantially in alignment with the chambers

Mounted in the valve chamber 75 is a valve element 79, which is engageable with a seat rib 80 and has a fluted stem 81 slidably disposed in a bore 82 connecting the valve chamber with the spring chamber 74, the valve element being thus disposed to control communication between the two chambers. A plunger 83 and biasing spring 82 are operatively mounted within the spring chamber 74, the spring being arranged to act through the medium of the plunger and stem 81 for urging the valve 79 away from the seat 80. The spring chamber 74 is connected to the main reservoir pipe 41a by way of a passage 84 having a restricted portion 85. Suitable air straining means 86 may be interposed in the passage 84, if desired.

Also mounted in the valve chamber 75 is a valve element 89, which is adapted to engage a seat 90 for controlling communication from the valve chamber by way of a bore 91 to a passageway 92, which in turn communicates with the drain valve pipe 65a and with a restricted atmospheric exhaust port 93.

For actuating the abutting valve elements 79 and 89 there is provided a valve piston 95, which is slidably mounted in the bore 76 and has formed on the upper side thereof a spring chamber 97 communicating with an atmospheric exhaust passage 98, and at the lower side thereof a chamber 99, which communicates with a timing chamber 100 formed in the pipe bracket 72. At the side adjacent the chamber 99, the valve piston 95 carries an annular seat rib 102, which is adapted to engage a gasket 103 while the piston valve is in the position in which it is shown in Fig. 2. An annular seat rib 105 is formed on the valve piston within the chamber 97, which seat rib is adapted for engagement with a gasket 106 upon upward movement of the element, as hereinafter explained. A coil spring 108 is interposed between the upper wall of the chamber 97 and a central wall 109 of the valve piston 95 for biasing it downwardly. The valve piston 95 is operatively associated with the valve element 89 through the medium of a plunger 111 engageable with the stem of the valve element, and a coil spring 112, which is interposed between the enlarged lower end of the plunger and an interior wall of the valve element, the plunger being guided in a suitable bore formed in the wall 109.

It will be understood that the valve piston 95 is of the snap-acting type, and to facilitate its operation a passageway 115 having a ball check valve 116 interposed therein is formed in the casing to provide communication from the portion of the chamber 99 surrounding the seat rib 102 to the atmospheric chamber 97. The timing chamber 100 which is connected to the chamber 99 also communicates with the valve chamber 75 by way of a passage 117 having a restricted portion 118. A branch 119 of the passage 117 bypasses the restricted portion 118 and opens into the valve chamber 75 by way of a port which is normally closed by a ball check valve 120.

In principle, the operation of the timing valve device 70 is similar to that of the corresponding device 4 shown in Fig. 1 of the drawing. Fluid under pressure is supplied from the main reservoir by way of the pipe 41a and flows through the passage 84 having the restricted portion 85 to the chamber 74, and thence through the bore 82 and past the normally unseated valve element 79 to the valve chamber 75. With the valve element 89 and ball check valve 120 seated as shown in Fig. 2, fluid under pressure can flow from the

valve chamber 75 only through the passage 117 having the restricted portion 118 to the timing chamber 100, and to the chamber 99 beneath the valve piston 95. The pressure of fluid in the timing chamber 100 and chamber 99 is gradually increased during an interval of time determined by the rate of flow through the restricted passage 118, and when this fluid pressure becomes high enough to overcome the downward force of the spring 108, the valve piston 95 is lifted to expose the full pressure area thereof to the chamber 99, and is then quickly forced to its upper seated position. Upward movement of the valve piston 95 is transmitted through the medium of the coil spring 112 and plunger 111 to the valve elements 89 and 79, which are thereby raised to their unseated and seated positions, respectively. The valve element 79 is thus positioned for cutting off further supply of fluid under pressure from the main reservoir to the valve chamber 75, while the valve element 89 establishes communication from the valve chamber to the passageway 92 leading by way of pipe 65a to the operating chamber of the associated drain valve device. The drain valve device is thereby operated to eject condensate as hereinbefore explained in connection with the apparatus shown in Fig. 1.

The compressed fluid effective in causing the operation of the drain valve device as just explained is supplied from the timing chamber 100 by way of the passage 117, branch 119, and past the ball check valve 120, which is unseated to allow the air to flow at a faster rate than can be obtained by way of the restricted passage 118 alone.

The pressure actuated elements of the drain valve device are then maintained in the positions to which they have been forced under the pressure of fluid in pipe 65a for a predetermined interval of time, which is terminated when the gradual venting of fluid through restricted port 93 has reduced the fluid pressure in the connected chambers 75, 100, and 99, sufficiently to permit the spring 108 to move the valve piston 95 downwardly. As the seat rib 105 on the valve piston is thus disengaged from the gasket 106, communication is momentarily established between the chamber 99 and the atmospheric exhaust chamber 97 by way of the passage 115 and past the ball check valve 116, and the resultant equalization of pressures of fluid below and above the valve piston facilitates the desired snap-action thereof, together with the associated valve elements 89 and 79, in assuming the positions in which these elements are shown in Fig. 2. The remaining pressure of fluid in the pipe 65a is quickly reduced to that of the atmosphere upon establishment of the communication between the passageway 92 and the atmospheric exhaust chamber 97. It will be understood that the drain valve device to which the pipe 65a is connected is thereby rendered operative again to discharge condensate from the associated reservoir.

It will be apparent from the foregoing description of two preferred embodiments of my invention that a timing valve means constructed in accordance therewith will be operative to effect quick and positive operation of an associated drain valve mechanism in cycles of operation that may be accurately predetermined, according to the pressure of fluid carried in the reservoir and the service for which the apparatus is intended.

Having now described my invention, what I claim as new and desire to secure by Letters Patent, is:

1. In an automatic drainage equipment for a fluid pressure receptacle, the combination of an automatic drain valve device having valve means responsive to variations in fluid pressure in a chamber for ejecting condensate deposited in said receptacle, and timing means comprising a casing having a timing chamber, a first valve controlling admission of fluid under pressure to said timing chamber, and snap-acting piston valve means cooperative with said first valve and also operative to control a communication from said timing chamber to said chamber in the drain valve device.
2. In an automatic drainage equipment for a fluid pressure receptacle, the combination of an automatic drain valve device having valve means responsive to variations in fluid pressure in a chamber for ejecting condensate deposited in said receptacle, and timing means comprising a casing having a timing chamber, a first valve controlling admission of fluid under pressure to said timing chamber, at a restricted rate, and snap-acting piston valve means cooperative with said first valve and also operative to establish a communication having one branch leading from said timing chamber to said chamber in the drain valve device and another restricted branch opening to the atmosphere.
3. In an automatic drainage equipment for a fluid pressure receptacle, the combination of an automatic drain valve device having valve means responsive to variations in fluid pressure in a chamber for ejecting condensate deposited in said receptacle, and timing means comprising a casing having a timing chamber, a first valve controlling admission of fluid under pressure to said timing chamber, a passageway in said casing connected to said chamber in the drain valve device and to a restricted vent port, and snap-acting piston valve means cooperating with said first valve and operative in one position to establish a supply communication between said timing chamber and said passageway, and in another position to cut off said communication to permit reduction in the pressure of fluid in said chamber at a predetermined rate.
4. In an automatic drainage equipment for a fluid pressure receptacle, the combination of an automatic drain valve device having valve means responsive to variations in fluid pressure in a chamber for ejecting condensate deposited in said receptacle, and timing means comprising a casing having a timing chamber, a first valve controlling admission of fluid under pressure to said timing chamber, and snap-acting piston valve means cooperative with said first valve and also operative to control a communication from said timing chamber to said chamber in the drain valve device.
5. In an automatic drainage equipment for a fluid pressure receptacle, the combination of an automatic drain valve device having valve means responsive to variations in fluid pressure in a chamber for ejecting condensate deposited in said receptacle, and timing means comprising a casing having a timing chamber, a first valve controlling admission of fluid under pressure to said timing chamber, another valve controlling communication from said timing chamber to said chamber in the drain valve device, and fluid pressure responsive means controlled in accordance with variations in the pressure of fluid in said timing chamber for actuating both of said valves.
- 10 6. In an automatic drainage equipment for a fluid pressure receptacle, the combination of an automatic drain valve device having valve means responsive to variations in fluid pressure in a chamber for ejecting condensate deposited in said receptacle, and timing means comprising a casing having a timing chamber, a first valve controlling admission of fluid under pressure to said timing chamber, another valve controlling communication from said timing chamber to said chamber in the drain valve device, and a reciprocating valve piston controlling communication from said timing chamber to said chamber in the drain valve device, said valve piston being constructed and arranged to move suddenly from one position to the other in response to predetermined changes in the pressure of fluid in said timing chamber.
- 15 7. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, snap-acting valve piston means subject to the pressure of fluid in said timing reservoir and operative to establish communication therefrom to said drain valve device, and yieldable means operatively connecting said piston valve means with the first named valve.
- 20 8. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, another valve controlling communication from said timing chamber to said drain valve device, and a reciprocating valve piston controlling communication from said timing chamber to said drain valve device, said valve piston being constructed and arranged to move suddenly from one position to the other in response to predetermined changes in the pressure of fluid in said timing chamber.
- 25 9. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, snap-acting valve piston means subject to the pressure of fluid in said timing reservoir and operative to establish communication therefrom to said drain valve device, and yieldable means operatively connecting said piston valve means with the first named valve.
- 30 10. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, snap-acting valve piston means subject to the pressure of fluid in said timing reservoir and operative to establish communication therefrom to said drain valve device, and yieldable means operatively connecting said piston valve means with the first named valve.
- 35 11. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, another valve controlling communication from said timing chamber to said drain valve device, and a reciprocating valve piston controlling communication from said timing chamber to said drain valve device, said valve piston being constructed and arranged to move suddenly from one position to the other in response to predetermined changes in the pressure of fluid in said timing chamber.
- 40 12. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, snap-acting valve piston means subject to the pressure of fluid in said timing reservoir and operative to establish communication therefrom to said drain valve device, and yieldable means operatively connecting said piston valve means with the first named valve.
- 45 13. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, another valve controlling communication from said timing chamber to said drain valve device, and a reciprocating valve piston controlling communication from said timing chamber to said drain valve device, said valve piston being constructed and arranged to move suddenly from one position to the other in response to predetermined changes in the pressure of fluid in said timing chamber.
- 50 14. An automatic timing valve mechanism adapted for association with a fluid pressure responsive drain valve device for a fluid pressure reservoir, comprising a casing having a timing chamber, a valve controlling admission of fluid under pressure from the reservoir to said timing chamber, snap-acting valve piston means subject to the pressure of fluid in said timing reservoir and operative to establish communication therefrom to said drain valve device, and yieldable means operatively connecting said piston valve means with the first named valve.

JOHN CANETTA.
